DESIGN FOR A KNEELING HAMMOCK

Melvin R. Grubb and Nerina C. Grubb,
Mission, Kans.

Application August 11, 1947, Serial No. 140,822

Term of patent 14 years

(Cl. D15—8)

To all whom it may concern:

Be it known that we, Melvin R. Grubb and Nerina C. Grubb, citizens of the United States, residing at Mission, in the county of Johnson and State of Kansas, have invented a new, original, and ornamental Design for a Kneeling Hammock, of which the following is a specification, reference being had to the accompanying drawing, forming a part thereof.

Figure 1 is a side elevational view of a kneeling hammock, showing my new design.

Fig. 2 is a top plan view thereof.

Fig. 3 is an end elevational view thereof; and
Fig. 4 is a perspective view thereof.

We claim:

The ornamental design for a kneeling hammock, as shown.

MELVIN R. GRUBB.
NERINA C. GRUBB.
